RECONDITIONING AND CONVERTING
CONTAINERS

Jacob S. Tucker, Cleveland, Ohio

Application March 3, 1947, Serial No. 731,941

3 Claims. (Cl. 220—61)

1

This invention relates to containers of the class known as steel drums, steel barrels, etc., and more particularly relates to reconditioning used containers for resale and concurrently converting them from one type to another.

Steel barrels, etc., as used in commerce after being emptied of the contents of their first use, such as paint, oil, etc., are not fit for reuse because of the residue therein of the original contents. A considerable business has developed in the reconditioning of such used barrels for reuse. They are cleaned out inside by various process, repaired if necessary, and repainted outside; and there is a ready market for them because they can be thus reconditioned and sold for profit at a price competitive with that of new barrels.

Steel barrels, drums, etc. are generally of two types: those having permanently closed heads at both ends and provided with a bung for filling and discharging the contents; and those that at one end have a sealed removable head or cover for access to the interior.

A concern in the business of reconditioning used barrels, buys both types in odd lots and in quantities and stores them, and they become his raw stock, from which he reconditions them in regular production on orders.

It frequently occurs however that the market demand for barrels of the removable cover type exhausts the raw stock of that type. This situation could be met by converting used barrels of the permanently closed type into barrels of the removable cover type, and the obvious procedure would be to cut off one end of the body of a permanently closed barrel and reconstruct that end to be like those originally made that way. When this is attempted, however, the cost of the conversion of the used barrels is too high to compete with new ones; because it involves a complete fabrication process including machinery for rolling over the end of the barrel body, to provide the usual rounded or rolled chine which the trade demands, etc.

Such reconversion furthermore includes the manufacture of the removable head and some kind of gasket to seal it on the end of the barrel.

Now the permanently closed type of used barrels in the raw stock storage of a concern engaged in the reconditioning business, purchased as they are in odd lots at different sources, and having been made by different original manufacturers, are of different diameters. Steel barrel containers for example of the fifty gallon size vary in diameter from twenty-two inches to twenty-two and one-half inches. To provide re-

2

movable heads and sealing gaskets for them of the usual construction would require the making of heads and gaskets of corresponding different diameters, which would add still more to the cost of the conversion process, dies, machinery, etc.

The problem then is presented, first, of devising a short cut process and a construction, by which a permanently closed barrel or the like may be converted to one having a removable sealed head and which may be practiced at small cost; and second, to provide a construction of removable cover and sealing gasket of a single diameter, which can be applied equally well in thus converting barrels of a wide range of commercial diameters.

It is the object of this invention to solve this dual problem.

The invention itself is set forth in the appended claims; and an illustrative embodiment of the invention is fully described in the following specification, taken in connection with the accompanying drawing, in which:

Fig. 1 is a longitudinal sectional view of one end of a steel barrel, or the like, of the permanently closed type, showing the conventional construction of the closed end and chine thereof; and which is to be converted into a removable cover type as hereinbefore referred to, by the practice of the invention;

Fig. 2 is a view of the parts of Fig. 1 showing some of the steps of the conversion process; and illustrating certain relations of the barrel chine and a separately made head and gasket construction, when the barrel body is one of maximum diameter, in a range of diameters;

Fig. 3 is a view of the parts of Fig. 2 showing a clamping ring added thereto by which the head is sealed upon the chine of the barrel by the gasket construction;

Fig. 4 is a view similar to Fig. 3 illustrating the same head and gasket construction as in Fig. 3, but in the case of a barrel of minimum diameter in the range of diameters;

Figs. 5, 6, and 7 are fragmentary views corresponding to parts of Figs. 2, 3, and 4 respectively, illustrating modifications of the gasket construction and of the clamping ring;

Fig. 8 is a fragmentary elevational view of a part of the clamping ring taken in the direction of the arrow 8 of Fig. 3 or Fig. 4;

Fig. 9 is a view taken in the direction of the arrow 9 of Fig. 8;

Fig. 10 is a top plan view of a hand operated clamping device for operating the clamping ring in the process of sealing the head on the barrel;

Fig. 11 is a fragmentary sectional view from the plane 11-11 of Fig. 10.

Referring to the drawing, I have shown in Fig. 1 one end of a conventional steel barrel or drum (the other end being substantially the same) and both ends thus being of the permanently closed type. The construction comprises a sheet metal cylindrical body side wall 1; a head 2 having a head body proper 3; and a side wall 4 telescoped into the body wall 1 and the outer ends of the two walls rolled over as at 5 and making a sealed chine having an outer rounded chine end or edge 6 and inwardly thereof an external chine shoulder 7. In the practice of the invention, I prefer to start with a drum of this construction.

As shown in Figs. 2 and 3, a large opening 8 is cut out of the original head body 3; as illustrated, the entire head body is cut away, but a smaller opening may be provided, if preferred.

A detachable head 9 is formed by stamping and pressing operations, to have a central head body proper as at 10; and a side wall 11, at the outer end of which is a radially outwardly extending flange 12 formed to have an axially inwardly concave channel 13 therein.

With the purposes of the invention in mind as referred to hereinbefore, the head thus formed is to be attached to drums of different diameters in a range of commercial diameters; and, as will appear, in mounting it, the concave channel 13 is in general nested with the chine 5, or concavely confronts it. In order that, as referred to, a single size or diameter of head may be used with drums of the entire range of diameters, the side wall 11 of the head is made of sufficiently small diameter to telescope within a drum of the minimum diameter and this is shown in Fig. 4; the same head being shown in Figs. 2 and 3 telescoped into a drum of the maximum diameter.

Also in order that the head channel 13 will nest with the chines of the entire range of diameters, it is made of sufficiently greater radial width than the chine, Fig. 4 showing it nesting with the chine 5 of the minimum diameter drum, and Fig. 3 showing it nesting with the chine 5 of the maximum diameter drum.

As will be described, the head 9 is clamped downwardly upon the drum end, with the chine 5 and head channel 13 nested together, and with a sealing gasket therebetween.

In Figs. 2 to 4, one form of gasket is shown, this form being in two parts 14a and 14b functioning as a one piece gasket.

The gasket part 14a is annular and U-shape in cross section, straddling the chine 5. For minimal cost, it may be formed from tubing of rubber or the like, split longitudinally along one side, cut to suitable length, bent into an annulus, and the ends secured together in any suitable manner, for example, by adhesive. The side walls of the U-shape lie along the inner end and outer walls of the chine but stop short of the shoulder 7. The diameter of the annulus may be made suitable for a drum of minimum diameter in the range, and may be stretched to fit drums of the maximum diameter.

The other portion 14b of the gasket is also an annulus of rubber or the like. It may be made from a strip of rubber, for example of rectangular cross section, cut to length and the ends secured together. It is placed in the head channel 13 substantially filling it from side to side, and may therefore be of a single diameter

for all diameters of drum, and if desired may be secured in the head channel by adhesive to facilitate assembling operations.

The head 9 is detachably mounted on the drum by a sheet metal clamping ring shown generally at 15. This ring is of channel section, concave radially inwardly, bent into the form of a split annulus with a gap 16 at the split. It is telescoped downwardly over the head channel 13 and chine 5 and is then in the condition shown in Fig. 10; and then as illustrated in that figure, a constricting and clamping tool 17 is associated therewith. The tool comprises a channel-form tool annulus shown generally at 18 split to provide a gap 19 and embracing the clamping ring 15 and lying thereon, being supported by tongues 20-20 overlapping the clamping ring 15. Arms 21-22 spaced apart at opposite sides of the gap 19 are pivoted to the two parts 23 and 24 of a toggle lever mechanism, pivoted together at 25; one of the parts being extended into a handle 26. By operating the handle in a well known manner the tool annulus 18 is constricted and constricts the clamping ring 15.

Constricting of the clamping ring moves it to position of Fig. 3 or Fig. 4, where as seen, its channel flanges engage the upper side of the head channel 13 and the shoulder 7 at the underside of the chine, and draws them together, putting the gasket 14a-14b under sealing compression.

The clamping ring 15 has a pair of eye lugs 27 and 28 welded thereto near the split 16 in the ring, and after it is in clamped constricted condition, a bolt 29 is passed through the eye lugs, and a nut 30 is put on the bolt to hold the ring in that condition; after which the clamping tool may be removed.

The chine 5 will be under a radially inner part of the gasket annulus 14a-14b for drums of small diameter as shown in Fig. 4; and under a radially outer part for large diameter drums as shown in Fig. 3; but will seal equally well for all diameters in the said range. Likewise the radially outer side wall 31 of the head channel 13 will project farther into the channel of the clamping ring 15 in one case as in Fig. 4 and not so far as in Fig. 3 but will work equally well in both cases, the depth of the clamping ring channel 15 being predetermined for this purpose.

The gasket as a whole seals both upon the chine and upon the head as will be understood.

In Figs. 5 to 7 is shown a one piece gasket 32 and a different sectional form of clamping ring 33, the latter having more nearly planar or flat channel walls than the curved-section ring of the preceding figures. The one piece gasket 32 is made from extruded rubber or the like formed to have a U-form or J-form section at the lower part to straddle the chine 5; and an upper part extending above the chine and having a sealing surface 34 to be clampingly engaged by the head channel 13; and between the chine 5 and the sealing surface 34 has interiorly thereof an annular cavity 35 to render it compressible. When the gasket is compressed by applying the clamping ring 33 (as described above for the clamping ring 15) it seals on both the chine 5 and on the head 9; and for drums of small diameter takes up the compressed and deformed shape of Fig. 7, and for large diameter drums, that of Fig. 6. The great radial extent of the head channel 13 leaves space for the deformed gasket to expand laterally.

into the spaces as shown at 36 and 37, Figs. 6 and 7.

The gasket 32 also may be made into the form of an annulus by cutting off a suitable length of the extruded rubber, bending it to annular form, and securing its ends together; and to fit the chines of all diameters would be made of suitable diameter for the minimum diameter chine, and stretched to fit the maximum diameter chine.

The U-shape or J-shape of the gaskets 14a or 32 above described, enable them to grip the chine and stay in position during assembly and disassembly of the head, particularly after being stretched to accommodate them to the large diameter chines, and they may be further facilitated by means of a coating of cement on the chine before being first fitted thereon.

The head 9 can in each case above described be removed upon removing the bolt 29 and allowing the clamping ring 15 (or 33) to expand back to its original unconstricted condition; and upon then removing it.

I claim:

1. A container of the steel drum class comprising a sheet metal tubular body having a side wall of circular section, a sheet metal head having a tubular side wall of circular section, telescoped into the body side wall, and the two side walls rolled upon each other at their tubular ends and providing a chine, having a rounded annular end edge, and having a shoulder on the outside of the body side wall spaced from the end edge; a large access opening through the head; an annular gasket of rubber or like compressibly deformable material having a concave annular recess fitting over and embracing the chine and having recess side walls terminating short of the said shoulder and the recess bottom engaging the rounded end edge of the chine, and the gasket having a sealing surface axially outward of the chine; the annular gasket being formed to normally fit upon the aforesaid chine when the drum is of minimum diameter in the range of commercial diameters, and the gasket material being elastic to cause the gasket to fit as aforesaid upon the chine when the drum is of the maximum diameter in said range; a circular sheet metal head having an annular side wall telescopable into the drum side wall at the chine end, and the head side wall terminating axially outwardly in a radially outwardly extending flange formed to provide an annular channel concavely confronting the gasket covered chine; the head side wall being of a diameter to telescope as aforesaid into the drum when it is of the aforesaid minimum diameter; the channel being of greater radial dimension than the gasket covered chine to concavely confront as aforesaid the gasket covered chine of the drum when its diameter is any diameter in the aforesaid range of diameters; a sheet metal, annular, radially inwardly concave, channel-form, split, clamping-ring, formed to embrace between its channel side walls the head channel axially outwardly thereof and the said chine shoulder, when radially constrictingly contracted, and to sealingly press the head channel bottom upon the said gasket seal-

ing surface and the gasket recess bottom upon the chine end; and detachable means to retain the constricted clamping ring in constricted clamping condition to sealingly, detachably, mount the head on the drum.

5 2. A container of the steel drum type comprising a head at one end having the metal of the head rolled with that of the drum body into a chine, with an exterior chine shoulder at an axially inner portion of the chine; a large access opening in the head; a detachable cover having a side wall of predetermined diameter small enough to telescope within the drum end when the drum is of the minimum diameter in the 10 range of commercial drum diameters; the side wall of the head terminating in a flange overlapping the chine; the flange having a channel therein concave toward the chine; the channel being of predetermined radial extent great enough to nest with the chine when the diameter 15 of the chine is any diameter in said range of commercial diameters from the minimum up to and including the maximum diameter; a gasket of rubber or like material between the head channel bottom and the chine; a split clamping ring of channel section constrictingly embracing the head channel and the chine shoulder, and compressing the gasket between the channel bottom and the chine; and detachable means to hold 20 the ring constricted to detachably sealingly mount the head on the chine.

3. A container of the steel drum type comprising a head at one end having the metal of the head rolled with that of the drum body into a chine, with an exterior chine shoulder at an axially inner portion of the chine; a large access opening in the head; a detachable cover having a channel therein concave toward the chine, and the channel being of predetermined radial extent 25 great enough to nest with the chine when the diameter of the chine is any diameter from the maximum diameter to the minimum diameter in the range of commercial diameters; a gasket of rubber or like material between the bottom of the head channel and the chine; a split clamping ring of channel section constrictingly embracing the head channel and the chine shoulder and compressing the gasket between the channel bottom and the chine; and detachable means to 30 hold the ring constricted to detachably sealingly mount the head on the chine.
